CLAIM

The ornamental design for a light, as shown and described.

DESCRIPTION

FIG. 1 is a top perspective view of a light illustrating my new design.

FIG. 2 is a bottom perspective view.

FIG. 3 is a top view.

FIG. 4 is a bottom view.

FIG. 5 is a front view.

FIG. 6 is a rear view.

FIG. 7 is a right-side view; and,

FIG. 8 is a left-side view.

Portions of the light are shown in broken lines. Portions shown in broken lines form no part of the claimed design. The light is shown with a symbolic break in its height. The appearance of any portion of the article between the break lines forms no part of the claimed design.

1 Claim, 8 Drawing Sheets
